HOSIERY

Russell W. Carley, Wauwatosa, Wis., assignor to
 Phoenix Hosiery Company, Milwaukee, Wis., a
 corporation of Wisconsin

Application July 15, 1935, Serial No. 31,439

8 Claims. (Cl. 66—172)

This invention relates to hosiery and more particularly to half-hose or men's socks.

The general purpose and object of my invention is to provide hosiery of this character and more particularly men's socks of regulation length as established by the United States Bureau of Standards with an arrangement of elastic yarns incorporated in the tops or welts of the socks to render them self-supporting on the leg of the wearer without discomfort by reason of the elastic yarns gripping about the wearer's leg when the socks are worn.

In men's socks of regulation length, the tops or welts at the upper ends of the socks extend up on the fleshier portion or calf of the wearer's leg from the more solid portion just below the calf where the tops or welts join the leg portions of the socks. In accordance with my invention, the elastic yarns referred to are so arranged in these top or welt portions that the greater tension required for the proper support of the sock on the leg of the wearer is provided in the regions best suited for this purpose without increasing the tension of the individual yarns.

In carrying out these objects, I arrange the elastic yarns in groups along the length of the top or welt and preferably provide the terminal groups adjacent the upper and the lower ends of the top or welt with a greater number of said 20 yarns in each terminal group than any of the intermediate groups. In this way a greater tension is available in the terminal groups to effectively support the sock on the leg of the wearer, without increasing the tension of the individual 30 yarns making up the several groups.

The lower terminal group or groups are adjacent the upper end of the leg portion of the sock and the elastic yarns of these groups encircle and grip the wearer's leg at the more or less solid 40 part immediately below the calf to properly hold up the leg portion of the sock on the leg of the wearer. The upper terminal group on the other hand grips about the calf at the upper edge of the sock and properly holds up the top or welt of the sock on the calf.

The intermediate groups by reason of their smaller number of elastic yarns provide less tension on the leg of the wearer and being spaced along the length of the top or welt serve to properly support the intermediate portions of the top or welt on the wearer's calf. As the yarns of the intermediate groups provide less tension than the terminal groups, there is less gripping on the leg of the wearer along the softer portion of the calf 50 and the sock can be worn without discomfort by

reason of the elastic yarns incorporated in its top or welt construction.

The elastic yarns are incorporated in the top or welt in the manufacture of the top or welt by laying or knitting in the yarns. The top or welt is knitted, comprising interengaged or interlocked loops disposed in successive courses and wales. The courses extend circumferentially of the top or welt, the latter being tubular in form, being produced on a circular top or welt knitting machine. The elastic yarns when laid in, engage the loops in the selected courses at the points of interconnection of the loops and extend in a straight direction throughout the courses, the ends of these yarns being tied or knotted together, 15 preferably where the courses join, so that the yarns may stretch longitudinally when the top or welt is distended in fitting about the leg of the wearer. In a knitted construction, the elastic yarns form the courses in which they are incorporated and stretch longitudinally when the top or welt is distended. The elastic yarns in each group are knitted or laid in the successive courses of the group. Thus in the terminal groups the yarns include a larger number of successive 20 courses than in any intermediate group. Moreover, the stretching of the top or welt to fit about the leg of the wearer is facilitated by having the groups spaced apart a reasonable number of 25 courses. This provides freely and readily distensible knitted portions of the top or welt free of elastic yarns between the several groups of such yarns. This arrangement also enables the top or welt of the sock to respond easily to the 30 muscular action of the calf in the movement of the leg without discomfort by the tension of the elastic yarns incorporated in the top or welt construction.

The yarns of all of the groups are preferably of substantially the same size and tension so that the individual yarns may be laid in the top or welt from the same source and at an initial tension sufficient to be stretched without exerting an undue pressure on the wearer's leg even at the calf, yet return the top or welt to its normal tubular form when not in use.

In the accompanying drawing illustrating my invention, Fig. 1 shows my improved sock as it appears in use on the leg of a wearer;

Fig. 2 is a view principally of the top or welt to more clearly show the group and spacing arrangement of the elastic yarns in the top or welt in accordance with my invention; and

Fig. 3 is a diagrammatic view showing the man-

ner in which the elastic yarns are laid in the selected courses of the top or welt.

The sock shown in the drawing is of the regulation length. It has a leg portion 1, a foot portion

5 2, and a top or welt 3. The latter fits about the leg of the wearer in the manner shown in Fig. 1. It will be noted that the top or welt has a length to extend well up on the calf of the leg from a point below the calf where the top or welt joins

10 the leg portion 2 of the sock.

The elastic yarns, marked 4, 4 in the drawing, are incorporated in the top or welt 3 as the top or welt is knitted on a circular knitting machine of the character employed for top or welt knitting.

15 If the top or welt is ribbed, which is usually the case, a so-called rib knitting machine is employed to produce the top or welt.

The yarns 4, in accordance with my invention, are arranged in spaced groups along the length 20 of the top or welt with the terminal groups *a*, *b* adjacent the upper and the lower ends, respectively, of the top or welt, as shown in Figs. 1 and 2. The intermediate groups *c*, *d* are spaced from each other and from the terminal groups *a*, *b* a 25 predetermined number of courses. Each group of elastic yarns comprises a plurality of such yarns, the terminal groups *a*, *b* each comprising a greater number of said yarns than any intermediate group. In the particular embodiment 30 of the invention disclosed herein, the terminal groups *a*, *b* each comprise six elastic yarns, while the groups *d* each comprise two elastic yarns, and the group *c* comprises four elastic 35 yarns.

35 With the group arrangement disclosed, the terminal groups *a*, *b* afford a greater tension than an intermediate group and thus the greater tension is available at the regions best suited for the proper support of the sock on the leg 40 of the wearer. The lower group *b* embraces the more or less solid part of the leg just below the calf and thus may grip sufficiently tight to hold up the leg portion 1 of the sock without wrinkle or sag. This is augmented by the group *c* next 45 above the group *b*.

The group *a* grips about the fleshier part of the leg constituting the calf and being at the upper end of the sock, holds up the top or welt 3. With a large number of elastic yarns in this 50 group, the tension of the stretched yarns is so distributed over the region of the group that the grip on the fleshier part of the leg is not so tight as to be uncomfortable or hinder the circulation of the blood in the leg.

55 The intermediate groups *d*, by reason of their fewer number of elastic yarns, exert less tension when stretched than the other groups, and thus may fit about the calf of the leg and conform to the varying contour thereof without undue 60 pressure. As these groups are spaced along the length of the top or welt, they conform the top or welt throughout to the leg of the wearer and aid in properly supporting the top or welt.

The yarns 4 of the several groups are laid or 65 knitted in the top or welt 3 at a slight initial tension so that the yarns will return the top or welt to its normal form when not in use. The tension of the individual yarns is substantially the same throughout all of the groups, and this 70 tension is not enough to cause a single yarn to so tightly grip the leg of the wearer as to bind even on the fleshier portion or calf of the leg. The increased tension required at the terminal groups *a*, *b* and *c* is obtained by increasing the 75 number of said yarns, thus avoiding any undue

gripping on the leg of the wearer as would be occasioned by increasing the tensions of the yarns themselves.

As shown in Fig. 3, the top or welt is a knitted structure comprising an arrangement of interengaged or interlocked loops arranged in successive courses and wales. The courses, indicated by *e*, extend circumferentially of the top or welt while the wales, indicated by *f*, extend longitudinally of the top or welt. The elastic 10 yarns 4 are laid in this structure in the manner shown in Fig. 3. This follows the usual laying in practice in rib knitting, and as shown in Fig. 3, the elastic yarns 4 extend lengthwise of the courses in which they are laid and are interengaged with the loops of these courses along the points of their interconnection. The yarns extend continuously along the selected courses and have their ends tied or knotted together at a selected point in the course, preferably at or 20 adjacent the rear of the top or welt where the courses are interlocked as in top or welt structures of this general character. Thus, the courses and the yarns may stretch when the top or welt is distended, the yarns being laid in the 25 top or welt at a slight tension as heretofore described.

As indicated in Fig. 3, the elastic yarns 4 are laid in successive courses, and this is followed for all of the groups. Thus, the yarns in each 30 group are in closely arranged relation, each group taking in as many successive courses as there are yarns in the group. The spacing between the groups is preferably a reasonable number of courses, so that knitted sections of 35 the top or welt free of elastic yarns are provided between the several groups. This, as heretofore stated, facilitates distension of the top or welt and conforms the top or welt to the wearer's leg, yet allows free muscular movement without 40 hindrance or binding by reason of the grip of the elastic yarns even about the fleshy portion of the calf. I find in actual practice that an eighteen course spacing between group *b* and the top of the leg portion of the sock and between group *a* and the group *d* next below and a fourteen course spacing between the other 45 groups produces a satisfactory product. I do not wish to be limited, however, to this particular spacing arrangement, the latter being cited 50 merely as an example.

It will be noted from Fig. 2 that the top or welt is more or less uniform in diameter throughout the portions occupied by the several groups of elastic yarns and thus these yarns 55 are more or less substantially equal in diameter in the finished hose. They are sufficiently elastic, however, to accomplish the objects of the invention and provide an effective self-support for a sock of the character described.

A regulation length sock offers less sales resistance to the general run of customers than the shorter or the longer socks. Moreover, the regulation length sock fits up on the calf of the leg for all leg lengths; instead of above the calf 65 for the longer socks or below the calf for the shorter socks. The regulation length sock also has the advantage of covering the desired portion of the leg, and with the elastic yarn arrangement of my invention incorporated in the sock 70 as herein disclosed, such socks may be made effectively self-supporting without discomfort by reason of the elastic yarns encircling and gripping the leg in the region of and about the calf 75

The details of structure shown and described 75

may be variously changed and modified without departing from the spirit and scope of my invention, except as pointed out in the annexed claims.

5. I claim as my invention:

1. A stocking having a knitted top or welt and elastic yarns incorporated in the top or welt and extending circumferentially thereof, said yarns being arranged in groups spaced along the length of the top or welt in selected of the courses thereof, the terminal groups adjacent the upper and the lower ends of the top or welt, each occupying a greater number of courses than any intermediate group whereby the terminal groups when stretched will exert a greater contractile force than an intermediate group.

2. A stocking having a knitted top or welt and elastic yarns incorporated in the top or welt and extending circumferentially thereof, said yarns being arranged in groups spaced along the length of the top or welt in selected of the courses thereof, the terminal groups adjacent the upper and the lower ends of the top or welt and the group next adjacent the lower terminal group, each occupying a greater number of courses than any of the other groups whereby the groups occupying the greater number of courses will exert a greater contractile force when stretched than a group occupying a lesser number of courses.

3. A stocking having a knitted top or welt composed of interlocked loops arranged in successive courses and wales, and elastic yarns extending circumferentially of the top or welt in certain of the courses thereof, said yarns being arranged in groups and having their ends secured together in their respective courses, there being a plurality of said yarns in each group and occupying the successive courses thereof, the groups being spaced apart along the length of the top or welt a predetermined number of courses free of said elastic yarns to facilitate distending the top or welt.

4. A stocking having a knitted top or welt composed of interlocked loops arranged in successive courses and wales, and elastic yarns extending circumferentially of the top or welt in certain of the courses thereof, said yarns being arranged in groups and having their ends joined together in their respective courses, there being a plurality of said yarns in each group and occupying the successive courses thereof, said groups being spaced apart along the length of the top or welt a predetermined number of courses free of said yarns, and certain of the groups each comprising a greater number of elastic yarns than the others whereby the groups having the greater number of elastic yarns when stretched, will ex-

ert a greater contractile force than any group having a lesser number of said yarns.

5. A stocking having a knitted top or welt composed of interlocked loops arranged in successive courses and wales, and elastic yarns extending circumferentially of the top or welt and laid in certain of the courses thereof, said yarns being arranged in groups spaced along the length of the top or welt and having their ends joined together in their respective courses, there being a plurality of said yarns in each group and occupying the successive courses thereof, certain of the groups each comprising a greater number of elastic yarns than others, and the elastic yarns of the several groups each having substantially the same tension.

6. A stocking having connected foot, leg, and top or welt portions, the latter being at the upper end of the leg portion, and elastic yarns incorporated in the top or welt in groups to provide a self-support for the stocking on the leg of a wearer, said groups being spaced along the length of the top or welt and arranged with the terminal groups adjacent the ends of the top or welt and the intermediate groups between the terminal groups and spaced from one another and the terminal groups by portions of the top or welt free of elastic yarns.

7. A stocking having connected foot, leg, and top or welt portions, the latter being at the upper end of the leg portion and consisting of a knitted structure composed of interlocked loops arranged in successive courses and wales, and elastic yarns incorporated in the top or welt in groups to provide a self-support for the stocking on the leg of the wearer, the yarns of each group being laid in the courses of the top or welt and occupying as many successive courses thereof as there are yarns in the group, said groups being spaced along the length of the top or welt and arranged with the terminal groups adjacent the ends of the top or welt and the intermediate groups between the terminal groups and spaced from one another and the terminal groups by portions of the top or welt free of elastic yarns.

8. A man's sock of regulation length having a knitted top or welt to embrace and fit about the calf of the leg of a wearer, and elastic yarns incorporated in the top or welt in the courses thereof, and arranged in groups along the length of the top or welt in a manner to provide terminal groups adjacent the ends of the top or welt and intermediate groups between and in spaced relation to each other and to the terminal groups to provide a self-support for the sock on the leg of the wearer.

RUSSELL W. CARLEY.
